UNITED STATES PATENT OFFICE.

PHILIP NATHANIEL BRAUN, OF SYRACUSE, NEW YORK, ASSIGNOR TO NATIONAL CHEMICAL COMPANY, OF SYRACUSE, NEW YORK, A CORPORATION OF NEW YORK.

COLLAR-IRONING MACHINE.

1,208,086.

Specification of Letters Patent. Patented Dec. 12, 1916.

Application filed June 8, 1914. Serial No. 843,716.

To all whom it may concern:

Be it known that I, PHILIP N. BRAUN, of Syracuse, in the county of Onondaga, in the State of New York, have invented new and useful Improvements in Collar-Ironing Machines, of which the following, taken in connection with the accompanying drawings, is a full, clear, and exact description.

This invention relates to certain improvements in collar-ironing machines of the class set forth in the patent to W. J. Quinn No. 792,454 issued June 13, 1905, except that it refers more particularly to the circular collar-supporting plate upon which the folded collars are placed by hand preparatory to subjecting the fold to pressure in a suitable shaping head for smoothing the folded edge of the collar. These collars are usually folded on a line parallel with but at one side of the lengthwise seam uniting the front to the back so that the fold is always at the side of the seam adjoining the front portion of the collar to avoid any appearance of the seam and it, therefore, follows that the fold must include the hemmed ends of the exposed front portion of the collar where they meet at the front of the neck, thereby producing an extra thickness the width of the hem at the ends of the fold.

In the use of the rigid collar-supporting plates heretofore employed, particularly in ironing the edges of collars in which the hems at the front ends of the fold were of considerable thickness there was always more or less liability of subjecting the folded portions of the hem to excess pressure while other portions adjacent such folded hem would be left more or less rough by reason of the inequality of pressure at the thick and thinner portions of the folded edge.

My object, therefore, is to overcome this objectionable result by making portions of the edge of the collar supporting plate upon which the collar is placed and particularly those portions where the hems at the ends of the collars rest sufficiently resilient to yield under pressure relatively to other por-

tions of such edge during the pressing operation so that the exposed edge of the collar will have a continuous, smooth appearance. In other words, I have sought to provide the collar receiving edge of the plate with transversely yielding portions located at such relative positions and of such lengths that the hems at the ends of the collars of different sizes will be brought into contact therewith, when placed on the plate, so that when the collar is subjected to pressure, in a suitable shaping head, the thickened portions of such hems will cause a slight depression of the adjacent yielding edges of the plate and thereby allow the top edge of the collar to contact with the shaping head under nearly uniform pressure at all points, leaving such edge in a uniformly smooth condition, without liability of breaking or overstraining the threads of the fabric at the folded portions of the hems.

Other objects and uses will be brought out in the following description:

In the drawings—Figures 1 and 2 are perspective views of slightly modified forms of my improved collar supporting plate. Fig. 3 is an enlarged face view of the upper portion or collar receiving edge of the plate shown in Fig. 1. Fig. 4 is a face view of a further modified form of my invention, in which the ends of the spring arms extend to the collar supporting edge of the plate and are disconnected one from the other; so as to allow free and independent action of either one of them. Fig. 5 is an elevation, partly in section, of a collar ironing machine embodying my improved collar supporting plate.

In order that my invention may be clearly understood, I have shown a platform —7— on which is arranged a standard —8— which serves to support a shaping device or ironing head —9—. This shaping device comprises a jacket —10— having an inlet —11— and an outlet —12— for a heating fluid, such as steam, adapted to heat the ironing portion of the head which is formed with a groove —13— for the re-

ception, as hereinafter described, of the collar support having a collar thereon, to mold the collar under pressure.

Suitable guide brackets —14— are secured to the platform —7— and slidably mounted therein is a stem or shaft —15— having an arm —16— at its lower end which is connected by a strap —17— with a crank —18— on an operating shaft —19—. A lever —20— is formed at one end of the shaft so as to permit the same to be readily rotated. A cross strip —21— is secured to the upper end of the shaft —15— and has standards —22— at the ends thereof, to the upper end of which is pivoted an arm —23— having an upright —24— thereon. Each of the uprights —24— is adapted to support a collar supporting plate —1— secured thereto in any suitable manner. These plates are adapted to be moved successively and by hand into and out of registration with the shaping device —9— and be projected into the shaping device when in registration therewith by vertical movement of the shaft —15—.

In Figs. 1 and 3, I have shown a circular collar supporting plate —1— of thin spring metal, such as spring steel, divided through one side at —2— for permitting radial expansion and contraction to conform more readily to the size and form of the shaping head with which it is adapted to coact during the pressing operation, and also to compensate for any inequalities of thickness in different portions of the collar during such operation. The main feature of the invention, however, consists in providing the collar supporting edge of the plate with yielding portions —3— at or near the meeting ends or division —2— and of sufficient circumferential length to form yielding rests for the thicker portions of the folded hems at the ends of the collar, so that when the collar is subjected to pressure against a suitable shaping die, the portions of the collar supporting edge of the plate adjacent the thickened portions of the collar will yield and allow the exposed edge of the collar to be pressed with a uniform degree of smoothness at all points in its length. These results are accomplished effectively by providing the portions —3— of the plates with a series of diagonally disposed slots —4— forming intervening diagonally disposed spring arms —5—, the free ends of which may be united or covered by a yielding rim or coping member —6—, forming a continuous smooth surface for supporting the collar, as shown in Figs. 1 and 2, or may be free and disconnected, as shown in Fig. 4. When the rims —6— are employed, they are sufficiently resilient to allow any one or more of the free ends of the arms —5— to be sprung downwardly and laterally, independently of

the other arms, according to the position of the thickened portion of the collar, said arms being sufficiently stiff and resilient to return the rim to its normal position when the pressure thereon is relieved.

In Fig. 3, I have shown a collar α in section as resting upon the rim or coping member —6— and as provided with a thickened portion, such as a hem α' , at one end to illustrate the effect of pressure upon the collar at the thickened portion thereof, which causes a slight depression of the rim —6— at —6'—, thereby similarly depressing the free ends of the adjacent arms —5— against their own tension and allowing the upper surface of the folded edge of the collar to be smoothed in a straight line throughout its length, by contact with a suitable shaping head, not shown.

The slots —4— and spring arms —5— of the collar supporting plate, shown in Fig. 2, are very similar to those shown in Figs. 1 and 3 except that the arms are slightly wider, while the ends of the slots are offset laterally, thereby reducing the width of the arms at these points and increasing their resiliency or ability to yield under comparatively light pressure.

As previously stated, the free ends of the arms —5—, shown in Fig. 4, are disconnected, but disposed in close juxtaposition, and are slightly undercut in one edge near their ends to establish a substantially continuous working edge or rest for the folded edges of the collars and at the same time allow the free end of any one of the arms to yield transversely of the plate, independently of the other arms, in case an extra thickness of collar should be registered with that particular point of the plate.

It is obvious that many other modifications might be made for accomplishing the same results without departing from the spirit of this invention, the essence of which resides in a collar supporting ring having compressible edge portions arranged to underlie the folds in the hems near the ends of the collar, in combination with an ironing head, the ring and the head adapted to have relative movement for interfitting the ring with the collar thereon and the socket, to mold the collar under pressure.

What I claim is:

1. In a collar ironing machine, a circular collar supporting plate having portions thereof near one edge slotted diagonally to form resilient arms.
2. In a collar ironing machine, a circular collar supporting plate having diagonally disposed spring arms.
3. In a collar-ironing machine, a circular collar support having a series of yielding members arranged side by side about its axis, and means integral with said members

for holding them in concentric relation to said axis.

4. In a collar-ironing machine, a circular collar support having a portion thereof composed of series of vertically yieldable fingers, and an integral coping member covering the upper ends of said fingers.

5. In a collar ironing machine, a substantially circular collar support having a portion thereof composed of a series of diagonally disposed fingers.

6. In a collar ironing machine, a substan-

tially circular collar support having a portion thereof composed of a series of diagonally disposed yielding fingers, and a coping member covering the upper ends of said fingers. 15

In witness whereof I have hereunto set my hand this 6th day of June, 1914.

PHILIP NATHANIEL BRAUN.
